UNITED STATES PATENT OFFICE.

JOHN A. TWEIT, OF APPLETON, MINNESOTA.

RAIL JOINT.

1,426,618.

Specification of Letters Patent. Patented Aug. 22, 1922.

Application filed January 31, 1921. Serial No. 441,247.

To all whom it may concern:

Be it known that I, JOHN A. TWEIT, a citizen of the United States, residing at Appleton, in the county of Swift and State of Minnesota, have invented certain new and useful Improvements in Rail Joints; and I do hereby declare the following to be a full, clear, and exact description of the invention, such as will enable others skilled in the art to which it appertains to make and use the same.

This invention relates to a rail joint particularly designed to be applied to rails used in railway service. As is well known, it is the common practice to form the rail joints of the railroad rails by means of plates which are bolted to the sides of the rail ends. This method places a great strain upon the bolts passing through the plates in the rails as the ends of the rails are bent down as the wheels of the train trucks pass thereover.

It is an object of this invention to provide a rail joint in which the rail ends are supported against this downward movement and the load carrying stress applied to the rails is transmitted to the cross ties.

It is a further object to provide a rail joint which can be quickly and readily applied to a broken rail so that the same can be quickly repaired without waiting for the placement of a new rail, thus resulting in little stoppage of traffic.

These and other objects and advantages of the invention will be apparent from the following description made in connection with the accompanying drawings in which like reference characters refer to the same parts throughout the different views and in which—

Fig. 1 is a view in perspective of two rails joined by a novel rail joint;

Fig. 2 is a sectional view taken substantially on the line 2—2 of Fig. 1, also showing the side of the joint in perspective; and

Fig. 3 is a transverse section taken on the line 3—3 of Fig. 1.

Referring to the drawings, an ordinary type of railroad rail is shown as 1 and the end of a similar rail 2 is shown in abutting relation thereto. The rail joint of this invention comprises a member 3 which extends along one side of the rail and has a plate portion 4 upon which the rail rests, which portion extends under and beyond the lower flanges of the rail. The plate 3 is also pro-

vided with an upstanding portion 5 which is adapted to extend along the side of the rail and to contact therewith below the head or tread portion of the rail and also at the top of the lower or attaching flange of the rail. 60 The bottom part of the portion 5 thus forms with the plate portion 4 a recess into which the bottom flange of the rail fits, the sides of the recess being disposed at an angle approximately the same as that of the sides of 65 the rail flange. The plate portion 4 extends beyond the side edge of the upstanding portion 5 to form spaced flanges 6 which are adapted to be disposed over the cross tie members 7. These flanges 6 are provided 70 with spaced holes for receiving the holding spikes 9, these holes passing through the member 3 between the edges of the flange 6 and the upstanding portion 5. As clearly shown in Fig. 3, the outer side portion of 75 the member 3 is formed on an incline or bevel and a slight horizontal ledge is formed adjacent the vertical side of the portion 5. The heads of the spikes 9 are adapted to contact either with the bevel portion or with 80 the said ledge.

The rail joint also comprises a member 10 designed to extend along the side of the rail opposite to that supported by the member 3, and this member 10 is formed with an upstanding portion 11 which is arranged to contact under the head or tread portion of the rail and with the top of the bottom or attaching flange of the rail. The member 10 is provided with a lip or flange 12 extending downwardly along the side of the rail adjacent to the plate 4 of member 3. The portion 12 is also formed with a bevel or incline on its outer surface and also provided with a short horizontal portion forming a ledge adjacent the vertical outer surface of portion 11, and the portion 12 is also formed with slots 13 adapted to receive the attaching spikes 9, which spikes also pass through openings 14 formed in the end of 90 plate 4 and with which the slots 13 are arranged to register. The edges of the spikes 9 are adapted to engage with the horizontal ledge described or with the beveled portion 95 in the same manner as the spikes engage the 100 similar portions of member 3.

From the above description it is thought the structure and use of the rail joint will be readily understood. The part 3 is first placed in position and moved so that the 110

upstanding portion 5 comes into firm contact with the upper and lower portions of the rail. The lower flange of the rail will be held firmly in position in the angle or recess of the member 3, there being slight clearance between the side edge of the rail and the inner end of this recess, as shown in Figs. 1 and 3. The member 10 will then be pressed against the rail and brought into firm contact with the top of the rail flange and the lower part of the rail head. The rail will then be tightly held or clamped between the members 3 and 10 and these members can then be firmly secured in position by the securing bolts 15. The members 3 and 10 will then be secured to the tie by driving of the attaching spikes 9. It will be observed that the downward stress on the rail joint caused by the wheels passing thereover, will be supported by the plate 4 on the member 3 and the ends of the rails will be prevented from moving downwardly and thus placing a great stress on the bolts passing therethrough. When the rail joints are secured only by side plates, a great many securing bolts are broken, resulting in a large loss of material and many damaged rails and accidents. This loss and damage will be prevented by applicant's device.

The noise occurring when the track wheels run over a rail joint is also caused largely by the flexing of the rail ends. Such flexing will be prevented by the use of applicant's device and practically all of the noise of the wheels running over the rail joint will be eliminated. Another feature of utility of applicant's novel rail joint is in its use as a repair joint. If the rail is broken, the member 3 can be applied to the broken ends in the same manner as it is applied to the usual ends of the rail, as shown in Figs. 1 and 2. The member 10 will also be placed in position and the two members securely spiked to the cross ties. This will support the ends of the broken rail sufficiently well to allow considerable traffic to pass thereover and until such time as a new rail can be conveniently brought and placed in position. With this use of the device, it will be unnecessary to hold up the traffic on ac-

count of a broken rail until the new rail can be placed in position.

The parts of applicant's device are quite simple and require very little finishing or machine work. The members 3 can be made either by being rolled into shape or they can be made as steel castings. It will, of course, be understood that various changes can be made in the form, proportion and details of the device without departing from the scope of applicant's invention, which, generally stated, consists in the matter shown and described and set forth in the appended claim.

65

What is claimed is:

A rail joint structure having in combination a member having a plate portion upon which the rails are adapted to rest, said plate portion extending transversely beneath the rails and beyond the edge of the same, said member also comprising a portion extending over and contacting the top surface of the rail flanges and extending upwardly and contacting with the under-part of the rail heads, and provided with an intermediate longitudinally extending horizontal ledge, said member having spaced holes therethrough adapted to receive securing spikes, the heads of which are adapted to contact said ledge, a second member extending along the opposite side of the rails having a portion contacting with the top of the rail flanges and the underside of the rail heads and extending along the side of the rail flanges into proximity to said plate portion and also having an intermediate longitudinally extending ledge, said portion having openings in its outer edge adapted to receive securing spikes the heads of which are adapted to contact with said ledge and said plate portion having apertures therethrough disposed in alignment with said openings through which said securing spikes also pass.
